United States Patent Office.

T. M. CLUXTON, OF RISING SUN, ASSIGNOR TO HIMSELF AND GEORGE B. GARLINGHOUSE, OF NORTH MADISON, INDIANA.

Letters Patent No. 83,256, dated October 20, 1868.

IMPROVED HEAD-BLOCK FOR CARRIAGES.

The Schedule referred to in these Letters Patent and making part of the same.

To all whom it may concern:

Be it known that I, T. M. CLUXTON, of Rising Sun, in the county of Ohio, and State of Indiana, have invented a new and improved Head-Block for Carriages; and I do hereby declare that the following is a full, clear, and exact description thereof, which will enable those skilled in the art to make and use the same, reference being had to the accompanying drawings, forming part of this specification, in which—

Figure 1 represents a plan or top view of my improved head-block for carriages.

Figure 2 is a vertical sectional view of the same, taken on the plane of the line $x x$, fig. 1.

Similar letters of reference indicate corresponding parts.

My invention consists in a head-block for carriages and other similarly-constructed vehicles, made of malleable iron or other suitable material, in the shape of the letter T, with the upper portion of that part of it forming the shank of the T grooved out, for the front end of the reach to rest in, and in which it is secured by bolts or rivets, and the sides of it recessed to admit of side-braces secured thereon, by means of rivets, and the bottom of it suitably recessed, so as to admit of the application of a bottom-supporting plate, all of which go to firmly hold and support the reach. The top of the head-block, or that portion of it forming

the head of the T, is grooved out, to receive the front spring of the carriage.

In the accompanying drawings—

A represents the top of the head-block, and B, the shank.

C is the front end of the reach, embedded in the groove in the shank B, and the dotted lines $c c$ represent the bolts or rivets by which it is held therein.

D, fig. 2, represents the bottom-supporting plate of the reach C, and

E E, fig. 1, are the side-braces secured on the reach C by the bolt $e e$, and in the recesses on the shank B of the head-block by the bolt $e' e'$.

H represents the front spring of the vehicle as embedded in the groove in the top, A, of the head-block.

What I claim as my invention, and desire to secure by Letters Patent, is—

In the T-shaped head-block A B for carriages, the combination of the recessed extension-arm B with the supporting-plate D, and braces E E, arranged as herein described and set forth.

The above specification of my invention, signed by me, this 8th day of April, 1868.

T. M. CLUXTON.
